UNITED STATES PATENT OFFICE.

THOMAS HOTCHKISS, OF GILLESPIE, ILLINOIS.

CAR COUPLER.

Application filed February 21, 1925. Serial No. 10,893.

To all whom it may concern:

Be it known that I, THOMAS HOTCHKISS, a citizen of the United States of America, and resident of Gillespie, in the county of Macoupin and State of Illinois, have invented certain new and useful Improvements in Car Couplers, of which the following is a specification.

This invention relates to car couplers, and particularly to a coupler designed for use on mine cars or other dumping cars, and it is an object of this invention to produce couplers which, when properly set prior to the approach of one coupler with relation to the other, will automatically interlock in a manner to produce a strong, durable and efficient connection.

It is a further object of this invention to produce a coupler of the character indicated having means whereby the couplers may be used with links and pins, so that if parts of the automatic coupling devices are impaired, the cars may be used with such link and pin connections.

It is a still further object of this invention to produce a coupler of the character indicated having a draw-bar which is rotatably applied to the car or car frame so that the cars may dump sidewise without impairing the couplers or disconnecting the same.

With the foregoing and other objects in view, the invention consists in the details of construction, and in the arrangement and combination of parts to be hereinafter more fully set forth and claimed.

In describing the invention in detail, reference will be had to the accompanying drawings forming part of this application wherein like characters denote corresponding parts in the several views, and in which—

Figure 1 illustrates a top plan view of the car coupler heads connected together, associated with the fastenings for retaining them coupled;

Figure 2 illustrates a vertical sectional view thereof when in a coupled state;

Figure 3 illustrates a sectional view of fragments of the couplers in positions assumed during the coupling operation or the interengagement of the coupler heads;

Figure 4 illustrates a similar view show-

ing an advanced step in the coupling operation;

Figure 5 illustrates a view in side elevation of a coupling latch;

Figure 6 illustrates a vertical section on the line 6—6 of Fig. 5;

Figure 7 illustrates a side view of the main shaft;

Figure 8 illustrates an end elevation of the same;

Figure 9 illustrates a sectional view on the line 9—9 of Fig. 7;

Figure 10 illustrates a sectional view on the line 10—10 of Fig. 7;

Figure 11 illustrates a view in side elevation of the couplers in their coupled condition;

Figure 12 illustrates a view in elevation of the couplers in slightly separated positions;

Figure 13 illustrates a view in side elevation, partly in section, showing the link and pin connection associated with the said couplers;

Figure 14 illustrates an enlarged detail view of one of the coupler heads;

Figure 15 illustrates a top plan view thereof;

Figure 16 illustrates a central vertical longitudinal section thereof, taken on the line 16—16 of Fig. 15;

Figure 17 illustrates an end view thereof;

Figure 18 illustrates a transverse vertical section of the coupler on the line 18—18 of Fig. 16;

Figure 19 illustrates a view in side elevation, partly in section, of the coacting coupler head;

Figure 20 illustrates a top plan view thereof;

Figure 21 illustrates a longitudinal vertical section taken on the line 21—21 of Fig. 20;

Figure 22 illustrates a view in elevation of the front end of the said coupler head;

Figure 23 illustrates a view in elevation of the latch tripping device; and

Figure 24 illustrates a detail view of the coupling pin.

In these drawings, 30 and 31 denote the coacting coupler heads, and each is preferably associated with a draw-bar 32 rotatably mounted in a bracket or housing 33 which

may be attached to the car frame. The draw-bar has reciprocal motion in the frame or housing, and is associated with a spring 34 which serves to absorb jar and vibration, due to the action of the coupler. A draw-bar 32 is connected to each head by a pin 35, and preferably a buffer spring 36 is interposed between the coupler head and the housing. As shown in the drawing the said draw-bar is rotatable so that a car equipped with the coupler may turn sidewise independently of the coupler and without interfering with the interlocking engagement of the coupler heads of the two cars.

15 The coupler head 30, which may be termed a female coupler head, has a main shaft 37 extending transversely thereof, and the said shaft is rotatably mounted in the sides of the coupler head. The coupler head 30 has a recess or cavity to receive the projecting portions of the coupler head 31.

20

The main shaft has a portion between its ends shaped with a straight side 38 and an oppositely curved surface 39, which curved surface constitutes a cam to be engaged by the projecting portions of the coupler 31, for the purpose of imparting rotary motion to the said main shaft. The main shaft has portions 40 and 41 which are trunnioned in the side walls of the coupler 30 and it has ends which project beyond the side walls on which the body 42 of the latch 43 is secured in order that the latch will oscillate as the main shaft partially rotates. The coupler head 30 has lugs 44 on its sides near the lower edge thereof, and each side of the body of the latch has shoulders 45 which engage the lugs to limit the rearward oscillatory motion of the said latch. The coupler head 30 is also provided with apertured bosses 46 and 47 which are in vertical alinement on its side, for the purpose of receiving as a place of storage the coupling pin 48, when the same is not in use for connecting the couplers by link and pin. The upper and lower walls of the coupler head 30 have alining apertures 49 and 50 to receive the coupling pin 48 when the coupler heads are to be connected by a pin 48 and links such as 51 which are anchored to the opposite coupler head 31 in known manner.

It will be understood, therefore, that the coupler head 30 has provision for causing the coupler heads to be connected through the operation of the latch, or through the use of a link and pin.

When the coupler heads are to be connected and locked into engagement with each other by the latch, the hooks 52 of the latch interlock with lugs 53, both of which are formed preferably integral with the outer side of the coupler head 31, it being shown that the engaging surfaces of the hooks and the engaging surfaces of the lugs are complementary in configuration so that a close

joint or connection is established between these two interlocking members of the coupler.

The latch body has two cheek pieces, one of which swings parallel with and practically in engagement with one side of the coupler head 31, and the other cheek piece swings parallel and practically in engagement with the opposite side of the coupler head 31, and the hooks constitute extensions of said cheek pieces.

The coupler head 31 has an extension or nose 54 projecting from its forward end. This nose has parallel sides and it enters the recess or cavity in the front end of the coupler head 30. The extension 54 has a longitudinally extending slot 55 in its end that merges with a cavity 56 whose major axis extends vertically, and the cavity has a rear wall 57 which constitutes an abutment for the camming surface of the main shaft, and it is effective to partially rotate the main shaft when the two coupler heads have been forced together fully. The upper wall 58 of the extension formed in the production of the slot 55 coacts with the main shaft initially when the couplers are moved together, and the engagement of the upper wall 58 with the camming surface 39 of the main shaft serves to partially rotate the main shaft and raise the latch in order that a clearance may be produced for the movement of the coupler heads together. The partial rotation of the main shaft causes the parts to assume the positions shown in Fig. 4 of the drawings, and the flat side of the main shaft passes through the slot 55 to the cavity 56. As the coupler heads are further moved in the direction of the arrow shown in Fig. 4, the main shaft will be caused to strike the wall 57 of the cavity, and the camming action of these engaging parts will cause the latch to be swung downwardly in order that the hooks of the latch will interlock with the lugs 53 of the coupler head 31, and when the parts are in this interlocked state, the main shaft will appear in the cavity 56, as it is illustrated in Fig. 2 of the drawing. It is shown that that portion 59 of the extension below the slot 55 is shorter than that portion above the slot 55, and the portion 59 of the extension has a shoulder 60, which, with the shoulder 61 on the portion of the extension above the slot 55, will cooperate with the flat side of the main shaft so that the couplers cannot become unlocked until the latch is elevated manually.

As a means for swinging the latch upwardly, a cable or flexible element 62 has its ends secured in an eye 63 of the latch, and the said cable or flexible element 62 operates over a pulley or sheave 64 on a shaft 65 that may be operated by the crank handles 66 from either side of the car when the latch is to be moved for releasing the coupler

heads. From an inspection of the drawing and from the foregoing description, it will be apparent, therefore, that when the coupler heads are moved together, the extension 54
 5 will pass into the cavity of the coupler head 30, and the projection 58 of the extension 54 will engage the camming surface 39 of the main shaft and impart rotary motion to the said shaft. This motion, in turn, will
 10 be communicated to the latch and it will be elevated clear of the lugs 53 of the coupler head 31. When the coupler heads have been moved together to the limit of their capacity, the camming surface 39 of the main shaft will have engaged the rear wall 57 of the cavity 56 and a reverse partial rotation of the main shaft will be imparted to it, and the latch will descend so that its hooks will engage the lugs 53 of the
 15 coupler 31.

The coupler head 31 has a longitudinally extending slot 67 and transversely extending slots 68 and 68^a intersecting it, which constitute seats for a similarly shaped
 20 coupler lock shift pin 69 whose lateral extension 70 lies in the cavity 68 when in one position of adjustment.

The term "latch" has been used in referring to the element that engages the lugs 53 of the coupler head 31 and by that term it is to be understood that applicant intends to include any element that might be oscillatably supported by the main shaft to interlock with elements of the opposite coupler head substantially as the element functions in the invention disclosed herein.

The pin 69 may be employed for holding the latch closed when it is projected into the aperture 69^a formed in said latch, and when in said position, the extension 70 of the latch will be seated in the intersecting slot 68^a of the coupler head 31 so that the locking pin cannot be moved longitudinally until the lateral extension of the locking pin is raised
 45 from the seat 68^a.

The coupler heads have longitudinally extending channels 71 and 72, one on each side near the bottom, which are intended for electric cables and air line connections, respectively, when such equipment is desired.

The coupling pin has projections 75 extending from each side that are intended to enter recesses or slots 76 at the edge of aperture 49 of the coupler head 30. The recesses 76 communicate or merge with annular recesses 77, and it is the purpose of the inventor that the relation of parts shall be such that when the pin 48 is applied to the apertures 49 and 50 of the coupler head 30, the extension 75 of the coupler pin shall pass into the recesses 76 and the annular recesses 77 in order that when the pin is applied to the apertures 49 and 50 and turned slightly, the extension 75 of the pin will be out of registry with the recesses 76, a condi-

tion which will prevent the pin from being unseated when the cars are tilted. The boss 46 has recesses 46^a in its upper edge to receive the pins or extension 75 when the coupler pin is being stored.

The outer crank handle 66 may be manually operated from the side of the car and the inner crank handle 66 is intended to be tripped or moved by a tripping device which abuts the said inner crank handle as the car is moved toward the trip, although provision is made for displacing the trip so that it will not be in the path of travel of the inner crank handle when it is desired to allow cars to pass the location of the trip.

To the end just stated, a handle 80 is oscillatably mounted on a pivot 81. A link 82 has its ends mounted on pivots 83, one of which connects the link to the handle 80 and the other of which connects the link to the tripping arm 84, which tripping arm is oscillatable on a pivot 85, so that if the handle 80 is pushed or pulled to oscillate it on its pivot, the connection between it and the tripping arm 84 will result in moving the tripping arm out of the path of travel of the inner crank handle 66, and when in such position, the car will pass without the coupler being opened. By the use of a tripper of this kind, cars may be disconnected at any station having a tripper, or they may be disconnected at other localities by the use of the manually operated crank handle.

I claim:

1. In a car coupler, a coupler head having a cavity in its end, a main shaft rotatably mounted transversely of the coupler head in the said cavity, the said coupled head having a camming surface, a latch carried by the said shaft, a coacting coupler head having a projection adapted to enter the cavity of the first mentioned coupler head, the said projection having a construction for engaging the camming surface of the shaft for imparting rotary motion to the said shaft and oscillating the latch, a surface for engaging the camming surface of the shaft for turning the said shaft in an opposite direction when the coupler heads are together for moving the latch in an opposite direction, and coacting elements on the second mentioned coupler head engaged by the latch for locking the coupler heads together.

2. In a car coupler, a coupler head having a cavity in its end, a main shaft rotatably mounted transversely of the coupler head in the said cavity, the said coupler head having a camming surface, a latch carried by the said shaft, a coacting coupler head having a projection adapted to enter the cavity of the first mentioned coupler head, the said projection having a construction for engaging the camming surface of

the shaft for imparting rotary motion to the said shaft and oscillating the latch, a surface for engaging the camming surface of the shaft for turning the said shaft in an 5 opposite direction when the coupler heads are together for moving the latch in an opposite direction, coacting elements on the second mentioned coupler head engaged by the latch for locking the coupler heads together, and means for holding the latch in 10 said last mentioned position.

3. In a car coupler, a coupler head having a cavity in its end, a main shaft rotatably mounted transversely of the coupler 15 head in the said cavity, the said coupler head having a camming surface, a latch carried by the said shaft, a coacting coupler head having a projection adapted to enter the cavity of the first mentioned coupler 20 head, the said projection having a construction for engaging the camming surface of the shaft for imparting rotary motion to the said shaft and oscillating the latch, a surface for engaging the camming surface 25 of the shaft for turning the said shaft in an opposite direction when the coupler heads are together for moving the latch in an opposite direction, coacting elements on the second mentioned coupler head engaged by the latch for locking the coupler heads 30 together, and means exteriorly of the coupler heads connected to the latch for disengaging it from the coacting coupler head.

4. In a car coupler, a coupler head having a cavity in its end, a main shaft rotatably mounted transversely of the coupler head in the said cavity, the said coupler head having a camming surface, a latch carried by the said shaft, a coacting coupler head having a projection adapted to enter the cavity of the first mentioned coupler head, the said projection having a construction for engaging the camming surface of the shaft for imparting rotary motion to 40 the said shaft and oscillating the latch, a surface for engaging the camming surface of the shaft for turning the said shaft in an 45

opposite direction when the coupler heads are together for moving the latch in an opposite direction, coacting elements on the 50 second mentioned coupler head engaged by the latch for locking the coupler heads together, draw-bars connected to the said coupler heads, and means for rotatably mounting the draw-bars on cars. 55

5. In a car coupler, a coupler head having a cavity in its end, a transversely extending shaft rotatably mounted in the cavity, the said shaft having a portion provided with a straight side and the opposite curved side 60 forming a cam, a latch secured on the said shaft to be oscillated as the shaft partially rotates, a coacting coupler head having a projection adapted to enter the cavity of the first mentioned coupler head, the said extension being longitudinally slotted approximately centrally of its height, the said slot terminating in a cavity whose major axis extends vertically, the said cavity having a rear wall adapted to engage the camming surface of the shaft when the coupler heads are together, and the forward end of the projection above the slot being adapted to engage the camming surface of the said shaft for rotating the said shaft in a direction opposite to that in which it is rotated when it encounters the rear wall of the recess. 70

6. In a car coupler, a coupler head having a cavity in its end, a shaft rotatably mounted in the cavity transversely of the coupler head, a cam on said shaft, a latch carried by the shaft, a coacting coupler head having a projection adapted to enter the cavity, means on the projection engaging the cam for rotating the shaft in one direction, means on said projection in stepped relation to the first mentioned means for engaging the cam and rotating the shaft in an opposite direction, and a latch engaged means on the second mentioned coupler head with relation to which the latch is moved by the rotation of the said shaft. 80 85 90

THOMAS HOTCHKISS.
